VENTILATOR OF THE LOUVER TYPE

Joakim Lehmkuhl, Oslo, Norway

Application March 31, 1937, Serial No. 133,973
In Norway April 3, 1936

4 Claims. (Cl. 98—101)

The well known ventilators of the louver type for exhaust of air or the passing of fresh air into rooms comprise a number of pivotally mounted, above each other arranged louver plates which for the opening or closing of the ventilators are caused to turn about individual axes. These louver type ventilators comprise a number of disadvantages, one of which is that the ventilating hole does not become entirely uncovered. Furthermore, the louver plates which in the open position will remain in the passage of the air have an ability of gathering dust and other particles, which at many places has caused the Board of Health to refuse the use of such ventilators in rooms occupied by persons, for instance in kitchens and the like rooms, and finally these louver type ventilators comprise a number of sliding movements and parallel mechanisms for the operating of same, which operating means easily becomes out of order.

One object of the present invention is to provide a ventilator of the louver type, where the above mentioned disadvantages are not present, and generally speaking the invention consists in a method of hinging the individual plates, serving for the closing and opening of the ventilator in such a way that they during the opening or closing process of the ventilator will pass through movements generally corresponding to the movements of the folding doors, used for instance on vehicles for transportation of persons.

In order to construct a suitable arrangement of this type in combination with a ventilator, and keeping in mind the construction of the least number of different parts and also in order to avoid sliding actuating members, due to the fact that these easily get out of order or get stuck, the ventilator according to this invention is constructed in such a way that pairs of plates are hinged together at the same time as one of each pair is hinged to the ventilator frame on the one side and to the other plate on the other side, while the latter plate is provided with a rigidly mounted rod or bar, which at a suitable point, for instance substantially normal to the edge of the plate and substantially at the same distance from the plate as the width of same, by means of a link is hinged to a pivot point on the frame, which for instance is located substantially normal to the hinge point between the two plates and substantially at the same distance from this point as the width of the plate in such a way that a swinging movement of the former plate by means of a suitable actuating mechanism through substantially 90° will cause the other plate to follow

and place itself over the former plate or aline itself with the former plate, respectively for the opening and closing of the ventilator.

When constructing a ventilator according to this invention, one may follow the method which will be described in this description with reference to Fig. 7 in the drawings.

As a modified embodiment of the invention one will in some cases adapt another construction, where the two plates forming one pair are not rigidly hinged together, but where the plate which is hinged to the frame of the ventilator is provided with a sliding guide, in which the other plate is hinged, the latter plate in the same way as above described being provided with a rod or bar which in this construction is directly hinged to the frame of the ventilator at a point which is positioned substantially diagonally in relation to the hinge point of the former plate to the frame in a square which has the former plate forming the two sides respectively, when it is in closed and open position. This simple mechanism is constructed in such a way that one may actuate either the plate which is hinged to the frame or the rod which is rigidly fixed to the other plate, swinging either one of these through an angle of 90°, and this movement will cause that both plates will shift position from being placed one above the other in the open position and alined adjacent to each other in the closed position of the ventilator.

A further object of this invention is to provide suitable actuating means for hand operation of the ventilator which may be operated directly by hand as well as indirectly by means of a string to be pulled. This actuating mechanism comprises a circular disk or sector which is adapted to actuate the plates by means of suitable connecting rods, and which is provided with teeth or apertures which are in mesh with a pinion, arranged at 90° to the said disk or sector, the said pinion being directly or indirectly provided with a two-armed lever which for example at each end is provided with a string in such a way that the ventilator may be opened and closed by a pull in one or the other of these strings or by taking hold of the two-armed lever directly by hand and by turning same in the same way as a thumb screw.

A further object of the invention is with reference to the last paragraph to arrange the said two-armed lever in such a way with reference to the pinion or the shaft that the arms may be detached and mounted in different positions at an angle of 90° to each other in such a way that

the ventilator, when being mounted, may be arranged with the actuating mechanism at the under- or upper edge of the ventilator or on one of the sides of same.

5 According to the invention it is of interest, in order to reduce the width of each plate, to use two pairs of such plates to cover the opening in the ventilator. When doing this, two sets of actuating mechanisms for the movements of the 10 plates constituting each pair will be necessary, and according to this invention these two sets of actuating mechanisms are connected together in such a way that the movements performed by one 15 of these sets will be automatically transmitted to the other set.

In order that the invention may be easily understood, it will in the following be described with reference to the drawings, illustrating preferred embodiments of the invention.

20 In the drawings:

Fig. 1 illustrates a longitudinal section through a ventilator which is closed.

Fig. 2 illustrates a corresponding section through the same ventilator in partly open position.

25 Figs. 3 and 4 illustrate corresponding figures of another embodiment of the invention.

Figs. 5 and 6 illustrate a further embodiment of the invention.

30 Fig. 7 illustrates diagrammatically the geometrical construction of the operating mechanism for the plates.

Fig. 8 illustrates to a larger scale a detail of the actuating mechanism for the opening and 35 closing of the ventilator.

Fig. 9 illustrates this mechanism seen from the side and adapted to be used on a ventilator mounted in such a way that the actuating mechanism will be placed on the lower side of same.

40 Fig. 10 corresponds to Fig. 9 but illustrates the position of the actuating mechanism when arranged on one of the sides of the ventilator.

In the drawings, Figs. 1, 2, 3 and 4, 1 represents the frame and 2 a register which possibly may be 45 arranged in front of the ventilator, if desired. The opening of the ventilator between the two sides 1 of the frame is covered by means of four plates 3, 4, 5 and 6. The plates 3 and 6 are by means of hinges 7 and 8 hinged to each one of the 50 sides 1 of the frame. The plates 4 and 5 are by means of hinges 9 and 10 connected to each one of the plates 3 and 6.

At or near that end of the plates 4 and 5 which are opposite to the hinges 9 and 10, these plates 55 are provided with stiff rigidly attached bars or rods 11 and 12 which extend from the plates normal to these and which may have substantially the same length as the width of the plates. At the other end of the bars 11 and 12, these are 60 by means of hinges 13 and 14 connected to bars 15 and 16 which at the other end are hinged to pivot points 17, 18 on the frame. The length of the bars 15 and 16 may preferably correspond to the width of the plates, and the pivot points 17 65 and 18 may preferably be arranged normal to the plates in closed position and directly outside the hinges 9 and 10 and at the same distance from these as the width of each plate. The accurate position of these hinged points, however, and the dimensioning will be generally explained below with reference to Fig. 7.

In the embodiment illustrated in Figs. 1 and 2, an actuating mechanism 19 which in the drawings is shown as a sector, is pivotally attached 70 to 20 to the frame and is provided with an arm

21 which projects outside the frame of the ventilator. The sector 19 is provided with a roller or the like 22 which has guiding contact in a slot or the like 23 on the inside of the plate 3. The sector is furthermore provided with a hinge 24 whereto is attached a bar 25 which extends to the other end of the ventilator and which here is hinged to an arm 26 which is pivotally journaled at the point 27 on the frame and which is in rigid connection with another arm 28 which at its end has a roller or the like 29 which runs in a slot 30 in the plate 6.

5 In Fig. 1—as already mentioned above—the ventilator is illustrated in its closed position. If the ventilator is to be opened, the handle 21 is moved in the direction of the arrow 31 and the roller 22 will slide in the slot 23 and cause the plate 3 to swing about its hinge 7, whereby the hinge 9 will follow the path of the arrow 32. During this movement, the bar 15 will swing 10 about the point 17, at a beginning in such a way that the hinge point 13 will follow the path of the arrow 33, for thereafter under further movement of the plate 3 to turn around, following the arrow 34.

25 In Fig. 2 the ventilator is illustrated in partly open position. From this figure it will be seen how the different parts will move, if the arm 21 is moved further on towards the left side of the drawings. Then finally the plate 3 will take a 30 position on top of the side of the frame 1, while the plate 4 will take a position on top of the plate 3. Simultaneously with the above mentioned movements of the different parts on the left side 35 of the ventilator, these movements will by means of the rod 25 be transferred to the arm system 26, 28, and the plates 6 and 5 with corresponding rods 12 and 16 will take part in and perform the movements in a corresponding way. The ventilator is in the position illustrated in Fig. 2 opened 40 to an extent corresponding to A. If it is desired to close the ventilator, the arm 21 is moved opposite to the direction of the arrow 31 and the individual parts will again take the position which is shown in Fig. 1.

45 In Figs. 3 and 4 another embodiment of the ventilator as above described with reference to Figs. 1 and 2 is shown. In the main features the two ventilators correspond to each other, and the same reference numerals will be found to a 50 great extent on Figs. 3 and 4 which have already been used with reference to Figs. 1 and 2. The main difference between the two embodiments lies in that mechanism which is used for operating the ventilator. This comprises an actuating mechanism 35 which in the drawings is illustrated as a circle, turnably attached to the frame at 36 and provided with an arm 37 which projects outside the frame of the ventilator. The circle plate 35 is provided with hinges 38, 39, to which bars 40, 41 are attached, which extend relatively to 55 each side and are hinged to arms 42, 43, respectively on the plates 3, 6.

60 In Fig. 3 the ventilator is shown in its closed position. If it is desired to open the ventilator, 65 the handle 37 is moved in the direction of the arrow 44, and the rods 40, 41 will swing the plates 3, 6 about their hinges 7 and 8 at the same time as the hinges 9 and 10 will follow the path of the arrow 45. During this movement, the bars 70 15 and 16 will swing about the points 17 and 18.

65 In Fig. 4 the ventilator is shown partly open. From this figure it is shown how the different parts will move, if the arm 37 is moved towards the left side on the drawings. Finally the plates 3 75

and 6 will place themselves right against the sides of the frame, while the plates 4 and 5 will place themselves over the plates 3 and 6. For the closing of the ventilator, the arm 37 is moved 5 in the direction opposite to the arrow 44, and the different parts will again take the same position as shown in Fig. 3.

In the embodiment shown in Figs. 5 and 6, corresponding parts are marked with corresponding 10 numerals as in Figs. 1, 2, 3 and 4. In order to simplify the description, the movements of the plates 6 and 5 only will be described in this embodiment.

The plate 6 is hinged to the frame 1 by means 15 of a hinge 8 in such a way that the hinges may swing from the closed position shown in Fig. 5 according to the arc 46 to an intermediate position as shown in Fig. 6, or further in such a way that the plate 6 will place itself on top of the 20 side of the frame 1. The plate 5 is provided with a bar 47 which at the point 48 is hinged to the frame 1. The point 48 is arranged diagonally in relation to the hinge 8 in a square, where the plate 6 forms one side and the bar 47 the other 25 side. On the plate 5 or the bar 47 the roller 49 is arranged, having guiding in a slot 50 in the plate 6. This arrangement operates in such a way that if the bar 47 is sung about the point 48, then the roller 49 will follow the arc 51, and due 30 to the fact that this roller has guiding in the slot 50, the plate 6 will simultaneously swing about its hinge 8. While this swinging movement takes place, the point 52 on the plate 5 will move according to the arc 53, and when the bar 47 has 35 swung through an angle of 90°, the point 52 will have moved substantially to the point of location of the hinge 8 in such a way that the two plates 6 and 5 will be positioned on the top of each other against the side of the frame 1. The plates 40 6 and 5 will perform this movement whether the actuating mechanism is arranged in relation to the bar 47 or directly on the plate 6.

In order to make the two pairs of plates move simultaneously, an arm 54 with a sector 55 may 45 be provided, to which sector bars 56 and 57 are attached, said bars being connected to the bars 47 and 47'. The swinging movement of the sector 55 will thus cause the two pairs of plates 6, 5 and 4, 3 to be opened or closed simultaneously 50 and correspondingly.

In Fig. 7 is illustrated how it is preferred to go about the problem of deciding the different dimensions of the different parts of which the ventilator is constructed.

In this figure one will further find the same 55 numerals as used in Figs. 1, 2, 3 and 4; only half of the ventilator is shown, however, illustrating two parts. In order now to locate the point 18' and the length of the bar 16', one may while taking 60 into consideration the different dimensions of the available frame, choose the length of the stiff bar 12' which is rigidly attached to the plate 5' substantially according to wish. If thereafter one draws the plate 5' and the bar 12' in 65 the other extreme position, i. e. in the open position of the ventilator as shown in Fig. 7 with dotted lines, one will obtain two points 14', 14' on the constructional drawing. Between these two points, a line b is to be drawn, and in the 70 middle of this a perpendicular a is to be raised. The pivot point 18' for the bar 16' shall now—in order to obtain a correct result—be located on this line a, taking into consideration the different dimensions of the frame of the ventilator.

In Figs. 8, 9 and 10, a preferred embodiment

for the actuating mechanism for the plates described in the foregoing description is shown.

In these figures 35 denotes a disk which is turnably attached to the frame of the ventilator (not shown) by means of a shaft 36. The disk 5 35 may be formed as a sector. To this disk are pivotally attached bars 40, 41, forming connecting links between the disk 35 and the plates of the ventilator. The disk 35 is according to this invention provided with teeth or apertures 59, 10 extending along a greater or smaller part of its circumference.

On the frame of the ventilator there is further mounted a pinion 60 which is in mesh with the teeth 59 and which are journaled on the shaft 15 61, suitably arranged on the frame of the ventilator. On this shaft there is further arranged a two-armed lever 62, 63, which is attached to the pinion 60 by means of a thumb screw 64 and which is prevented from turning in relation to 20 the pinion by means of projections 65, 66, 67, 68, which may be arranged on the pinion or on a part directly or indirectly attached to same. The arms 62, 63 may for instance be provided with holes 69, 70, to which a string 71, serving to 25 actuate the arms, may be attached.

If the ventilator is mounted with the actuating mechanism in such a way that this will be positioned at the lower or upper edge of the ventilator, the arms 62, 63 must be attached to the 30 pinion 60 as shown in Fig. 9. If, however, the ventilator is mounted in such a way that the actuating mechanism will be positioned on one of the sides of the ventilator, then it is necessary to reset the arms 62, 63 in such a way that they in 35 spite of this turning of the frame of the ventilator itself, will take the position in relation to the horizontal which is shown in Figs. 9 and 10. This is done by loosening the thumb screw 64, whereafter the arms 62, 63 may be shifted 90°, 40 which will be seen from Fig. 10.

It will be understood from the above that this actuating mechanism is very suitable and will provide for an accurate opening and closing of the ventilator by means of a pull in a string 71. 45

In the foregoing description the present invention has been described with reference to ventilators of the louver type, and the object of the invention is also generally speaking to provide a good construction for this purpose. The arrangement according to this invention may, however, also to a great extent be used for other purposes of corresponding type and the special embodiment of the invention which has been described in the foregoing may in special cases with 55 advantage be used for opening and closing of doors and windows. The present invention thus also covers the described mechanism used for such purposes.

I claim:

1. A ventilator comprising an open frame of rectangular cross section adapted to be mounted in an air passage, the current of which is to be controlled, a plurality of shutter plates hinged together in pairs and adapted to cover or uncover the said frame, one plate of each pair of plates being hinged to the said frame along one edge and to the other plate along the opposite edge, the latter plate being provided with a fixed arm extending into the said frame and 65 being provided at its free end with a link pivotally fixed in one end of said arm and at the other end to the frame at a point remote from the plates in their closed position. 70

2. A ventilator comprising an open frame of 75

rectangular cross section adapted to be mounted in an air passage, the current of which is to be controlled, a plurality of shutter plates hinged together in pairs and adapted to cover or uncover the said frame, one plate of each pair of plates being hinged to the said frame along one edge and to the other plate along the opposite edge, a rigid arm projecting outwardly from the outer plate of each pair and being disposed at the edge of the plate, a link pivotally connected to each arm and to a pivot point on the frame, said point being located remote from the plates in their closed position.

3. A ventilator comprising an open frame of rectangular cross section adapted to be mounted in an air passage, the current of which is to be controlled, a plurality of shutter plates hinged together in pairs and adapted to cover or uncover the said frame, one plate of each pair of plates being hinged to the said frame along one edge and to the other plate along the opposite edge, the latter plate being provided with a fixed arm extending into the said frame and being provided at its free end with a link pivotally fixed in one end of said arm and at the other

end to the frame at a point remote from the plates in their closed position, an actuating mechanism comprising an arm extending outside and pivotally fastened to the frame, a sliding guide on one of the said plates engaged with said last named arm, whereby a swinging movement of the said arm will be transmitted to the said plate to open and close the same.

4. A ventilator comprising an open frame of rectangular cross section adapted to be mounted in an air passage, the current of which is to be controlled, a plurality of shutter plates hinged together in pairs and adapted to cover or uncover the said frame, one plate of each pair of plates being hinged to the said frame along one edge, a sliding guide on the first mentioned plate hinged to the frame, a hinge connection for the second plate and the frame comprising a member hinged to the frame, the axis of the hinge connection being disposed relative to the meeting edges of the two plates in the closed position and at a distance from said meeting edges equal to the width of one plate.

JOAKIM LEHMKUHL. 25
